(57) **CLAIM**

The ornamental design for a support structure for a furniture component, as shown and described.

DESCRIPTION

FIG. 1 is a perspective view of support structure for a furniture component, showing my new design;

FIG. 2 is a front view of the support structure for a furniture component shown in FIG. 1, with the rear view being a mirror image thereof;

FIG. 3 is a left side view of the support structure for a furniture component shown in FIG. 1;

FIG. 4 is a right side view of the support structure for a furniture component shown in FIG. 1;

FIG. 5 is a top view of the support structure for a furniture component shown in FIG. 1; and,

FIG. 6 is a bottom view of the support structure for a furniture component shown in FIG. 1.

The broken lines showing the worksurface furniture component, support plates and glides in the Figures are for environmental purposes only and do not form any part of the claimed designs.
